UNITED STATES PATENT OFFICE.

LOUIS LARSON, OF NEW YORK, N. Y.

MULTIPLE-WALL LAMP SHADE.

Application filed December 23, 1925. Serial No. 77,244.

My invention relates to improvements in lamp shades, globes, or the like, and particularly has to do with spaced multiple-walled construction adapted to receive a colored fluid therein, or a colorless fluid, such as water.

One of the objects of the invention resides in the provision of a globe having means between the reader and the source of light for diffusing and softening the rays of the latter.

Another object is to provide a globe having a multiplicity of colored sections, said colored sections being varied at the will of the user.

A further object is to provide a globe or shade which may be inexpensively manufactured, absolutely fireproof, and one presenting a neat and attractive appearance.

Other objects and advantages will be apparent as the nature of the invention is better set forth, and it will be understood that changes within the scope of the claim may be resorted to liberally without departing from the spirit of the invention.

In the drawings, forming a portion of this specification and in which like numerals of reference indicate similar parts in the several views;

Figure 1 is a central vertical sectional view of my improved globe;

Fig. 2 is a view like unto Fig. 1, but showing the construction for providing a multiplicity of chambers between the walls and also means for admitting a current of air through the interior of the globe; and

Fig. 3 is a similar sectional view depicting a shade constructed in accordance with my invention.

The globes illustrated in Figs. 1 and 2 are primarily intended for use in connection with electric lighting, while the shade shown in Fig. 3 is especially adapted for gas lighting or kerosene lamps, but, of course, may be used in conjunction with the well-known incandescent lamp and its fixtures.

The construction shown in Fig. 1 comprises a body portion 5, designed with free flowing curves and fillets to present a striking neat appearance and being circular in horizontal cross-section.

Said body portion consists of inner and outer spaced walls, 6 and 7, respectively, slightly spaced apart to define a chamber 8 which extends completely around the sides

and bottom of the body portion, and a portion of the top, as clearly shown in the drawing. I provide the top of my globe with an upwardly diverging annular rim 9, having a bead 10, for connection with a standard electric light fixture (not shown).

Within said chamber 8 may be introduced a colored fluid, or even water, through the aperture 11, the latter being provided with a closure 12 having an opening 13 from which steam generated by the heat from the lamp 14 may escape. While the possibility of such generation is exceedingly remote I prefer to have this opening as a precautionary measure.

In the event water is introduced into the chamber 8, it is obvious that the rays of light passing therethrough are considerably softened in tone and at the same time said rays are diffused with greater luminosity. For decorative purposes it may be desirable to fill the chamber with colored water of different hues and thus create beautiful color effects within a room.

The structure shown in Fig. 2 is somewhat similar to that of Fig. 1, but in this instance I provide the globe with a bottom opening 15 to provide ventilation for the interior of the globe, and further I provide the chamber 8 with partitions 16, so that in fact I now have a multiplicity of chambers, each having filling apertures and closures as in my other form. While the drawing shows these partitions 16 as arranged with some degree of regularity, it should be understood that they may be positioned angularly, vertically and even horizontally in order to provide what might be termed "sub-chambers", each having filling means for the introduction preferably of colored fluids. In the drawings these sub-chambers have been lined to illustrate some of the colors which may be used, and it is quite obvious that a judicious use of coloring material therein will result in the production of an article exceedingly beautiful in appearance and attractive to the eye.

Figure 3 illustrates the body portion 5, having a flared lower portion, and the usual walls 6 and 7 defining the chamber 8. This sort of shade is adapted for other lighting purposes than electric, if desired, and in this construction the source of light throws its rays downwardly through the flared portion and obviously is unaffected by the fluid in the chamber. The rays emerging from

the side of the lamp, are, of course, subjected to the softening action of the contained fluid.

From the foregoing it is manifest that I have devised a globe or shade which is extremely useful, since it not only removes the harshness of the rays of light, but further is an article beautiful and artistic in appearance.

10 I claim:

An article of the class described comprising a bulbous body portion embodying parallel spaced walls defining a narrow chamber therebetween, the outer wall extending 15 from the top of the body portion and rolling

upon itself to define a bottom opening in the body portion, and merging with the inner wall, said inner wall continuing upwardly and having its upper portion diverging to define a flange for sealing the space between itself and the outer wall and projecting above said outer wall for attaching the body to a support, and a plurality of annular partitions arranged in the space between said walls and defining therein a plurality of chambers each having an inlet for the admission of a colored fluid.

20 In testimony whereof I affix my signature.

25 LOUIS LARSON.
